ENVELOPE

Eugene B. Berkowitz, Kansas City, Mo.

Application January 12, 1935, Serial No. 1,514

8 Claims. (Cl. 229—74)

This invention relates to envelopes and particularly to one of the tag type that is attached to a package or other article to contain an enclosure such as a way ticket, bill of lading, memorandum, or the like, the principal objects of the invention being to provide an envelope of this character which is of stronger construction to withstand wear and tear incidental to shipping practices, to provide an envelope construction which better protects its contents from the elements, to provide an envelope which is self-opening upon pressure applied to the sides thereof when held between the fingers and thumb of the hand, and to provide an envelope which is more attractive and finished in appearance.

In accomplishing these and other objects of the invention, as hereinafter pointed out, I have provided improved details of structure, the preferred form of which is illustrated in the accompanying drawing, wherein:

Fig. 1 is a perspective view of the upper portion of a milk can illustrating the attachment of a tag envelope embodying the features of the present invention.

Fig. 2 is a perspective view of the rear side of the envelope, the flaps being shown in closed position and a strand extending through the openings in the envelope to attach it to an object, such as the can illustrated in Fig. 1.

Fig. 3 is a perspective view of the envelope blank prior to folding.

Fig. 4 is a perspective view showing the side flaps in folded position and the top and bottom flaps in extended position prior to folding.

Fig. 5 is a detail section through the closure flap end of the envelope, particularly illustrating the six thicknesses of material through which the attaching strand is extended.

Fig. 6 is a cross-section through the envelope on the line 6—6, Fig. 2.

Fig. 7 is a perspective view of the completed envelope showing the method of opening the mouth thereof to insert or remove a way bill or the like.

Referring more in detail to the drawing:

1 designates an envelope constructed in accordance with the present invention and formed from a blank 2 which includes a front portion 3 and flaps 4 and 5 extending coextensively with the opposite sides of the portion 3 and foldable thereover to form the back portion 6 of the envelope.

The flaps 4 and 5 have a combined width greater than that of the front face portion 3 so that they overlap a material distance when in folded position as shown in Fig. 6 to reinforce the length of the envelope and to provide a seam of extra thickness through which the attaching strand is extended as later described.

Formed on the lower end of the front face portion 3 and extending across the width thereof is

a flap 7 adapted to fold over the lower ends 8 and 9 of the flaps 4 and 5 that form the back of the envelope.

The upper end of the front portion has a closure flap 10 preferably having an arcuate outer edge 11 of different radius than the corresponding edges 12 and 13 of sectional flaps 14 and 15 that are formed respectively on the upper ends of the flaps 4 and 5.

The flap 4 and bottom flap 7 are provided with spaced parallel gum stripes 16—17 and 18—19 to seal the flaps when the blank is folded as now to be described.

The flap 5 is folded over the inner face of the front portion 3, after which the flap 4 is folded over the outer face of the flap 5 and the flap 7 is folded over the lower ends 8 and 9 of the flaps 4 and 5 to form an envelope closure. The adhesive stripes 16—17 and 18—19 are preferably dried under pressure to give what is known as a welded effect, thereby establishing very rigid and water proof joints which are not subject to deterioration by the elements.

When the envelope is folded as above described, the closure flap 10 on the front portion 3 and the closure flap 20 that is formed by the flap sections 14 and 15 project outwardly from the planes of the front and back sides of the envelope as illustrated in Fig. 4. The flap 10 being of different curvature is preferably of longer length than the flap 20 to provide a lip portion 21 which extends over the edge of the flap 10 to form a water shed when the flaps are folded as later described.

After the envelope is folded, as above described, the body portion thereof is provided with an opening 22 extending through the overlapped seam of the back portion of the envelope and an aligning opening 23 in the front portion 3. The closure flaps 10 and 20 are also provided with openings 24 and 25 of larger diameter than the openings 22 and 23 in the body portion, but which have their centers located at substantially the same distance from the fold line 26 so that when the flaps 10 and 20 are folded over the back portion of the envelope, the openings 22 and 23 will align with the openings 24 and 25 to permit passage of a strand such as a wire or string 27 by which the envelope is attached to the package being shipped, for example, the milk can, as shown in Fig. 1.

It is, therefore, apparent that due to the arrangement of openings extending through the relatively wide seam and the double closure flaps, the wire is extended through six thicknesses of material as best illustrated in Fig. 5 so that it is not necessary to use reinforcing washers or grummets to prevent the wire from pulling through the envelope. It is also apparent that due to the lip 21, the outer closure flap extends

beyond the inner flap to enhance the finished appearance of the envelope and produce the water shed above noted.

In using an envelope constructed as described, 5 the way bill or the like is inserted through the mouth of the envelope and both closure flaps are folded back over the back portion of the envelope as shown in Fig. 2. A string or wire 21 is then passed through the aligning openings 10 to attach the envelope to the article being shipped.

In the case of the milk can as shown in Fig. 1, the tag may be attached by the sealing wire which seals the top of the can by passing one end of the wire through the openings in the envelope 15 prior to attachment of the seal. The seal, therefore, not only seals the can, but seals the way ticket or other memorandum enclosed in the envelope.

When the envelope is to be opened, the attaching wire 20 is removed and the closure flaps are unfolded so that they lie in the plane of the front and back portions of the envelope, whereupon the envelope is retained in the palm of the hand and gripped between the thumb and fingers 25 thereof. Upon pressure applied to the sides of the envelope, the mouth of the envelope will be caused to open as shown in Fig. 7 to permit ready removal or insertion of the contents.

From the foregoing it is apparent that I have 30 provided an envelope which is not only very convenient to use, but it is of strong construction and able to withstand exposure to the elements.

What I claim and desire to secure by Letters Patent is:

35 1. An envelope of the character described including a face portion having an opening therein, flaps overlying the face portion and having overlapping edges sealed to each other to form a relatively wide seam of double thickness and provided with an opening in registry with the first named opening, and extensions on said overlapped flaps and connected by said seam to form a closure flap having an opening therein extending through said seam and adapted to register 40 with said other opening upon folding of said closure flap to pass an attaching element there-through.

2. An envelope of the character described including a face portion having an opening therein, 50 flaps folded over the face portion and having overlapping edges sealed to each other to form a relatively wide seam of double thickness and provided with an opening extending through said seam in registry with the first named opening, a closure flap on the face portion having an opening therein adapted to register with the said other openings, and a closure flap similar to the first named closure flap and formed as a continuation of said overlapped flaps whereby said seam extends across said closure flap, said last named closure flap being provided with an opening 55 registering with said other openings when the closure flaps are folded together to closing position for passing an attaching element there-through.

3. An envelope of the character described including a face portion having an opening therein, side flaps overlying the face portion and having overlapping edges sealed to each other to form a relatively wide seam of double thickness substantially in the longitudinal center of the envelope 70

and provided with an opening extending through said seam in registry with the first named opening, a closure flap on the face portion having an opening therein adapted to register with said other openings, and a flap similar to the closure flap and formed as a continuation of the side flaps whereby said seam extends across said flap and provided with an opening registering with said other openings when the closure flap and said last-named flap are folded together to pass an attaching element therethrough. 5

4. An envelope formed of sheet material folded to form front and back portions to provide a pocket therebetween for an enclosure, a bottom flap on one end of one of said portions and sealed 15 to the other to close that end of the pocket, flaps on the opposite ends of said portions foldable back over each other and over one of said portions to close the opposite end of the pocket, and a seam extending longitudinally of one of said portions and extending through one of the last-named flaps, said envelope having an opening extending through said last-named flaps and seam whereby a strand passing through said opening 20 engages six thicknesses of material. 25

5. An envelope formed of sheet material folded to form front and back portions having an open mouth at one end through which an enclosure is inserted, a bottom flap on the opposite end of one of said portions and sealed to the other portion to close that end of the envelope, flaps on the mouth end of said portions foldable back over each other and over one of said portions to close the opposite end, and a seam extending longitudinally of one of said portions and through one of the last named flaps, the mouth of said envelope being adapted to open incidental to pressure applied to sides thereof when the envelope is held between the thumb and fingers of the hand. 30 35

6. An envelope of the character described including a face portion, flaps foldable over the face portion and having overlapping edges sealed to each other to form a relatively wide seam of double thickness, a closure flap on the face portion, and a closure flap similar to the first named closure flap and formed as a continuation of said overlapped flaps whereby said seam extends 40 across said closure flap. 45

7. An envelope of the character described including a face portion, flaps foldable over the face portion and having overlapping edges sealed to each other to form a face portion overlying the first named face portion to provide a pocket therebetween, a closure flap on the first-named face portion, and a closure flap similar to the first-named closure flap and formed as a continuation of said overlapped flaps whereby said seam extends across said closure flap, said face portions and closure flaps having aligning openings through which an attaching strand is passed. 50 55 60

8. An envelope formed of sheet material folded to provide front and back portions forming a pocket provided with an open mouth at one end and through which an enclosure is inserted, and flaps projecting from the front and back portions at said open mouth and foldable back over each other to close said mouth, said flaps and front and back portions having registering openings for passing a strand to secure the flaps in closed position. 65 70
